UNITED STATES PATENT OFFICE.

JOHN W. CRAW, OF NEW YORK, N. Y.

IRONING-MACHINE.

SPECIFICATION forming part of Letters Patent No. 593,566, dated November 16, 1897.

Application filed February 2, 1897. Serial No. 621,665. (No model.)

To all whom it may concern:

Be it known that I, JOHN W. CRAW, a citizen of the United States, residing at New York, in the county of New York and State of New

5 York, have invented certain new and useful Improvements in Ironing-Machines; and I do hereby declare the following to be a full, clear, and exact description of the invention, such as will enable others skilled in the art to

10 which it appertains to make and use the same, reference being had to the accompanying drawings, and to letters of reference marked thereon, which form a part of this specification.

15 My invention relates to an improved method of ironing, and I have to this end constructed the herein described and illustrated machine and shall in this specification outline the structural elements, of which some are fa-

20 miliar, but have been arranged differently in my machine in order to fulfil the object I have in view, in addition to which I also embody several new principles and mechanical combinations entirely unknown to this class

25 of machinery.

The object of my invention is to feed the material into the machine and have it pass from roller to roller by its own weight—in other words, by gravitation; secondly, by the

30 arrangement and action of the rollers and their steam-heated reservoirs with each other to cause the material to be finished on both sides with a smooth well-ironed surface.

To accomplish my object, I have constructed

35 a spring device that will control the pressure of each roller against the steam-chest, so as to prevent the continuous bearing of the roller against the reservoir or steam-chest, and have devised means by which the said

40 spring devices can be controlled from a hand-wheel on each side of the machine, and through the instrumentality of the levers supporting the rollers pivoted to the frame the rollers when swung out from the frame are

45 made easy of access when adjustment and repairs are necessary. These points will be found covered and brought out by the novel construction of my machine, including the arrangement of a series of rollers having the

50 same diameter with their centers in a vertical line, which has had the beneficial results as herein described, all of which I shall now

proceed to describe, and in so doing will call attention to the accompanying drawings, wherein like letters of reference indicate corresponding parts in the different views, and wherein—

Figure 1 illustrates a front view of my improved ironing-machine, showing the mutual position of the rollers and steam-chests with regard to each other and the pivotal action, as in the instance of the roller B³, the cap of spring device D³ removed and the bearings of the levers C³ cut through, showing the journals of the rollers lying in them and showing also the gearing operating the rollers. Fig. 2 is a side view of Fig. 1, illustrating the mode of attachment of the steam-chests and rollers to the side frame, but for the sake of clearness in illustration the link system connected with the springs is omitted in both Figs. 1 and 2. Fig. 3 is a section on line p q of Fig. 1, showing all the rollers and steam-chests cut through and indicating by the arrow-heads the travel of the material in its downward course from the curved board M² to the apron N and also the whole connection of the gearing system. Fig. 4 illustrates the same front view of my machine as Fig. 1, omitting the chests and showing the connecting-links and their ultimate attachment to the hand-wheels. Fig. 5 is a side view illustrating the same elements shown in Fig. 4. Fig. 6 is a detail view of my improved spring-cap, the supporting-lever of the roller, and the cam mounted on the bearing of said lever. Fig. 7 is an end view of Fig. 6; and Fig. 8 is a top view of the sleeve C⁶, as shown in Fig. 6.

A indicates one side frame of my machine. The other side frame A' is of the same construction. Between these frames are attached four rollers B', B², B³, and B⁴, supported in bearings in levers C', C², C³, and C⁴. These levers are held in their respective positions by spring devices D', D², D³, and D⁴, bolted to the frame by bolts E. As they are all constructed alike and similar in their action I shall only describe one in connection with detail view, Fig. 6. Said spring device is composed of a cap D⁵, having sliding in it a box D⁶, with a pin D⁷ projecting from the bottom thereof. Lying in the box D⁶ and coiled around the pin D⁷ is a spring D⁸, compressed between the bottom of the box and an exter-

nally-screw-cut nut D⁹, screwed into a similarly-screw-cut aperture in cap D⁵ and sliding loose on the pin D⁷, consequently controlling the action of the spring, thus regulating the pressure of box D⁶ on the cam, and when the cam projection is moved out of the way presses continuously inward in the direction of the arrow-head. Controlling this inward pressure is a screw-cut nut D¹⁰, fitted on the screw-cut end of pin D⁷, gaining thus this point that no pressure will be exerted on the bearing of the roller having cam attached or on the lever itself, and consequently no pressure will be exerted on the roller when the cam is turned out of the way of box D⁶, which was the object I had in view, thus preventing scorching of the material passing between the chest and the roller. In this connection it will be as well to describe one of the supporting-levers C⁴, its action and thereupon dependent usefulness in permitting the roller B⁴, if out of order, to be repaired or adjusted without detaching the said roller from the machine. The lever C⁴ (see Figs. 2, 4, and 5) being pivoted to the frame by bolt g' and supporting at its other end in the bearing F' one of the journals H of the roller B⁴ it will readily be seen, as illustrated by the dotted line (see Fig. 2) indicating lever C³ in connection with roller B³, that when the cap containing the spring is unscrewed from the frame the two levers can easily be swung outward, and, carrying the roller with them, it will be seen that the roller will be accessible to repairs, adjustment, and re-covering. In having described these rollers B³ and B⁴, with their supporting-levers and spring devices, I have described them all, as their construction and action are exactly alike.

Attached between the frames A and A' are, furthermore, heated reservoirs I', I², I³, and I⁴, each of which reservoirs have semicircular concave surfaces, into which cavities the respective rollers are pressed with just the necessary tension required to give the material the exact smooth surface required from said reservoirs or steam-chests. Taking I⁴ as an example, it is attached between the two frames by having the two extensions K' and K², terminating in journals K³ and K⁴, (see I⁴ in Fig. 1,) secured in the bearings K³ and K⁴, cast, respectively, on each frame, so that the steam-chest has a pivotal action on its journals, being secured to these bearings by washers and nuts.

It is thus seen that in having a certain number of rollers with their corresponding concave reservoirs, which reservoirs have for this special construction been furnished with a prolonged lip at the bottom extending past the center line through the roller centers, arranged as above described, a different method of ironing has been attained as differing from the methods attending other constructions, where, for instance, the concave reservoirs are rigidly attached to the framework. These reservoirs in their construction are caused to

pass the center line x y with the tapered lips L, so that they will feed, aided by gravity, material into the next set of reservoirs and 70 rollers. In other words, these lips must be placed with such accuracy above the mouth or opening formed by the underneath-placed reservoir and roller that the material, partly aided by the motion given to it by the revolving of the roller above and partly by its gravity, will be caught in the said mouth and proceed on its downward course in the machine from one set to the other. This can best be seen in Fig. 3, showing a sectional view of 80 reservoirs and rollers, the traveling of the material being indicated by the arrow-heads. Referring to the said view as explaining the entire working method of the machine, although forming no part of my invention, it 85 will also be seen here how the material is fed from the top of the stand M, having a recess M', containing the material ready for the process, which, having been fed into the first set of reservoir and roller over the curved 90 part M² of the stand M, passes from one set to another until it has passed between the bottom roller B' and reservoir I', where it is caught up by the apron N, which, connected appropriately with the other driving-gear of 95 the machine, carries the finished material to the table O. The means for giving revolving motion to the rollers are the gear-wheels attached to the end of the roller-journal supported in frame A' and connect in the 100 following manner with the motive power. Corresponding to each roller B', B², B³, and B⁴ are attached spur-gears W', W², W³, and W⁴. Gearing into gear W² is a pinion W⁵, which, as it is keyed on the same sleeve P as 105 the gear W⁶, said sleeve revolving on a pin P², attached to the frame A', the pinion and gear will revolve with it, and gear W⁶, gearing into a pinion W⁷, will be revolved by the said pinion W⁷, attached to one end of a shaft 110 V', which is secured in bearings on the two frames, and at the end opposite to the one carrying pinion W⁷ is a pulley which receives motion from some motive power or other, thus transferring the proper motion through the 115 above-mentioned gears to the rollers B', B², B³, and B⁴. The apron N, as seen in Fig. 3, is connected with the previously-mentioned gearing by pinion N', gearing into the spur-wheel W', and as this revolves it will carry 120 the apron along over the rollers, over which it is suspended sufficiently tight to prevent sliding.

The mechanical means that make the different spring devices act in unison I shall 125 next describe. As before stated, the box D⁶ acts upon a cam or projection C⁶, part of a sleeve C⁶ moving loose on the bearing F' of a lever C⁴. This sleeve has an arm C⁷ projecting from it, to which is pivoted a link C⁸. Link C⁸ on both sides of the machine connects thus the cam-sleeves on levers C³ and C⁴, and in like manner connecting-link C⁹ connects the cam-sleeves attached to levers C' and C²,

and the link C^{10} connects the cam-sleeves on the levers C^2 C^3 . Connecting this link system, formed by the three links C^8 , C^9 , and C^{10} , with a crank-lever C^{11} is a link C^{12} . The crank-lever C^{11} is attached to a rod C^{13} , which is pivoted between the frames A and A' , and two hand-wheels C^{14} are attached to said rod C^{13} . The entire movement moving the cam projections away from contact with boxes D^6 , speaking of both side frames, so that they will occupy, relative to the said boxes, the dotted position of cam-sleeve shown in Fig. 6, will thus be seen to be as follows: When either of the hand-wheels C^{14} (see Fig. 5) are given half a turn, so that crank-lever C^{11} occupies the position diametrically opposite, (indicated by the dotted delineation,) the link C^{12} , connected with the crank-lever C^{11} , will be elevated, and with that, being connected in the above-described manner, the other three pairs of links C^8 , C^9 , and C^{10} will be elevated, and as they are pivoted to the arm of the cam-sleeve lying around its respective bearing on the lever will bring the cam projection away from the box D^6 , and consequently away from any spring action, thus stopping the pressure of the roller against its corresponding steam-chest, which was the desired object.

In describing the component parts of this machine its mode of operation has been indicated so clearly that no summing up of the working thereof would seem to be necessary.

My machine has been found by me to possess the attributes, first, of giving a smooth desirable surface on both sides of the articles being operated upon; secondly, of preventing the crumpling or creasing better than other machines, and, finally, the adjustable arrangement of rollers and the spring devices

controlling their pressure against the respective chests obviates the scorching of the material; but

What I particularly claim, and pray protection for by Letters Patent of the United States of America, is—

In a machine of the character set forth, a series of rollers arranged vertically according to a center line through their individual centers, each operating in combination with a heated reservoir or steam-chest, a pair of levers having bearings, pivoted in the side frames, supporting the journals of each of said rollers, a loose sleeve having a cam projection pivoted to each bearing, a cap bolted to the side frame adjacent to each of the said bearings, a box, sliding in said cap, having a pin, an externally-screw-cut nut, fitting into a similarly-screw-cut aperture in the cap lying loose around the pin, a spring compressed between the bottom of said box and the nut screwed into the cap, and, surrounding the pin, the aforesaid sleeve with a cam projection having an arm, said arm pivoted to one of a series of links, one of said links, on each side of the machine, pivoted by an intermediate link to a crank secured to a rod pivoted between the two side frames, said rod operated by two hand-wheels, for the purposes as set forth, substantially as it is illustrated and described.

In testimony that I claim the foregoing I have hereunto set my hand this 19th day of January, 1897.

JOHN W. CRAW.
